UNITED STATES PATENT OFFICE

115,351

DESIGN FOR A COMBINED DISPLAY CASE AND STAND

Harry John Rask, Portland, Oreg.

Application February 23, 1939, Serial No. 83,155

Term of patent 7 years

To all whom it may concern:

Be it known that I, Harry John Rask, a citizen of the United States and a resident of the city of Portland, Multnomah County, and State of Oregon, have invented a new, original, and ornamental Design for a Combined Display Case and Stand, of which the following is a specification, reference being had to the accompanying drawing, which forms a part thereof.

Figure 1 is a perspective view of a combined display case and stand, showing my new design; Figure 2 is a side elevational view thereof on a reduced scale; and

I claim:

The ornamental design for a combined display case and stand, as shown.

HARRY JOHN RASK.
